UNITED STATES PATENT OFFICE.

HARRY W. STERTZBACH AND MERRITT R. HANSEN, OF COLUMBUS, OHIO, ASSIGNEES
TO THE BUCKEYE STEEL CASTINGS COMPANY, OF COLUMBUS, OHIO.

CAST CAR-TRUCK SIDE FRAME.

Application filed January 2, 1923. Serial No. 610,316.

To all whom it may concern:

Be it known that we, HARRY W. STERTZBACH and MERRITT R. HANSEN, citizens of the United States, and residents of Columbus, in the county of Franklin and State of Ohio, have invented certain new and useful Improvements in Cast Car-Truck Side Frames; and we do hereby declare the following to be a full, clear, 10 and exact description of the invention, such as will enable others skilled in the art to which it appertains to make and use the same.

This invention relates to cast car truck side frames of the integral journal box type, the object of the present invention being to produce a construction whereby the stresses will be more evenly distributed than in the construction previously employed 20 and deformation of the journal box will be avoided. In the construction heretofore generally used, the tension member of the truck has been joined to the journal box in such a manner that abrupt offsets were 25 formed. An offset of this sort is not capable of effectually withstanding the opposing forces of the compression and tension members. As the tension and compression members were joined to the box 30 at widely spaced points, a noticeable deformation of the journal box has occurred, and a particular object of the present invention is to connect the opposed compression and tension members with the journal box in 35 such a manner and in such close relation that "shear" will be practically eliminated from the box proper and deformation will be overcome. One form of the means by 40 which the objects of the invention are attained is illustrated in the accompanying drawings, and the invention resides in certain novel features which will be particularly pointed out in the claims following a detailed description.

In the drawings, Figure 1 is a side elevation of a portion of a side frame constructed in accordance with the present invention;

Figure 2 is a top plan view thereof;

Figure 3 is a bottom plan view of the same;

Figure 4 is a detail longitudinal section on the line 4-4 of Figure 2.

In the drawing, the reference numeral 55 1 denotes the compression member of the

frame, 2 designates the spring seat, and 3 the diagonal tension member, all of inverted channel form. 4 denotes the side column which usually extends between the spring seat and the compression member, 60 and 5 denotes the journal box formed integral with the outer ends of the compression and tension members. In the present invention, the transverse web or top plate of the tension member 3 merges into the 65 top plate 6 of the journal box at the point where said top plate of the journal box joins the inner side wall 7 of the box, as shown most clearly in Fig. 4. The compression member is united with the top 70 plate of the box at the outer side wall and the tension and compression members are thus brought close together while abrupt offsets are avoided inasmuch as the tension member is not carried across a corner 75 of the box or terminated below the top of the same. It will also be noted that the top or transverse web of the tension member merges directly into the top member 80 of the spring seat and thus forms a continuous direct connection between the top of the spring seat and the top of the journal box, avoiding abrupt offsets and producing an arrangement which will most effectually resist the strains imposed under 85 load. By merging the top plate of the tension member into the top plate of the journal box at the junction of the same with the side wall of the box, we are enabled 90 to provide the flared ribs 8 in the angles defined by the sides of the tension member and the side of the box so that the strains in this area are effectively distributed and the structure enabled to withstand the horizontal shearing action between 95 the compression and tension members.

Having fully described our invention what we claim as new and desire to secure by Letters-Patent, is:

1. A cast side frame for car trucks having an integral spring seat, journal box, and tension member, the top of the tension member forming a direct continuous integral connection between the top of the spring seat and the top of the journal box. 100

2. A cast side frame for car trucks comprising an integral journal box, spring seat, and tension member, the tension member being of inverted channel form with its transverse web forming a direct continuous 105 110

integral connection between the top of the journal box and the top of the spring seat.

3. A cast side frame for car trucks comprising a journal box, a compression member, a tension member, and a spring seat, the compression and tension members being of inverted channel form, the compression member being united with the top of the journal box at the outer side thereof and the tension member forming a direct continuous connection between the top of the journal box and the top of the spring seat.

4. A cast side frame for car trucks comprising a journal box, a spring seat, and a tension member of inverted channel form, the lower end of the tension member being integrally united with the top of the spring seat and the upper end of the tension member being integrally united with the top of the journal box at the junction of the same with the inner side wall of the box, and the top of the tension member forming a direct connection between the top of the journal box and the top of the spring seat.

5. A cast side frame for car trucks comprising a journal box, a compression member and a tension member, the compression

member and the tension member being of inverted channel form, the upper end of the top of the tension member being integrally united with the top plate of the journal box at the corner defined by the junction of said top plate and the inner side wall of the box and the top of the compression member being integrally united with the top of the journal box at the junction of the same and the outer wall of the box.

6. A cast side frame for car trucks comprising an integral journal box, and a tension member, the upper end of the tension member being united with the top plate of the journal box at the inner side wall of the box, and flared bracing ribs uniting the side of the box with the side plates of the tension member at the upper end of the tension member.

In testimony whereof, we have signed 50 this specification in the presence of two subscribing witnesses.

HARRY W. STERTZBACH.
MERRITT R. HANSEN.
